CHAPEL ALTAR RAIL UNIT

Cecile Farrand, San Francisco, Calif.

Application July 28, 1958, Serial No. 51,969

Term of patent 14 years

(Cl. D13—7)

The figure is a perspective view of a chapel altar rail unit.

The opposite side of the chapel altar rail unit is identical to that shown in the drawing except, of course, that the hinges do not appear on the opposite side.

I claim:

The ornamental design for a chapel altar rail unit, as shown and described.
